Attorney

UNITED STATES PATENT OFFICE.

CHARLES J. BELL, OF CHICAGO, ILLINOIS.

CAR-COUPING.

SPECIFICATION forming part of Letters Patent No. 229,660, dated July 6, 1880.

Application filed March 20, 1880. (No model.)

To all whom it may concern:

Be it known that I, CHARLES J. BELL, of Chicago, in the county of Cook and State of Illinois, have invented certain new and useful 5 Improvements in Automatic Railroad - Car Couplings, of which the following, in connection with the accompanying drawings, is a specification.

In the drawings, Figure 1 is a perspective 10 of a railroad-car provided with a coupling embodying my invention; Fig. 2, a vertical central section; Fig. 3, a top view, representing a modification in the arrangement of the coupling; and Fig. 4, a side view of the coupling 15 as arranged in the manner indicated in Fig. 3.

Like letters of reference indicate like parts.

My invention relates to that class of car-coupling in which the act of coupling is performed automatically, and which admits of 20 uncoupling without the necessity of any one going between the cars for that purpose.

The object of my invention is to improve the construction and operation of couplers of this class in the several respects hereinafter 25 referred to; and to that end it consists in the means, substantially as hereinafter set forth, which I employ for that purpose.

A represents a railroad-car, and B is a draw-head. C is the coupler. This coupler consists 30 of a block made either wholly of metal or of metal and wood combined in such manner as to secure durability and strength, and so as to constitute an integral piece or part.

D is the body of the coupler, and E a hook 35 extending outward from the central part of the body D. The outward end of this hook has two engaging-flanges, *a a*, both inclining inward or toward the car to which the coupler is applied, and one extending above and the 40 other below the connecting bar or arm *a'*.

In other words, the hook may be termed a "double hook," and in form somewhat resembles a dart or spear-head, as is clearly indicated in Figs. 1, 2, and 3. It would also be proper to 45 say that the forward or outward face or end of the hook E is beveled in opposite directions, and that its engaging-faces are inclined in a similar manner, though not necessarily to as great a degree, as the outer faces, or to such 50 an extent as to make the outer and inner faces parallel to each other.

F F are V-shaped recesses behind the flanges *a a*. The inclined faces forming the recesses F F meet each other in lines parallel to the outer edges of the flanges *a a*, and are set far enough back therefrom to allow the hook on one coupler to engage that on the other, and to be uncoupled therefrom, as is clearly indicated in Fig. 2. When the hooks are engaged the recesses F F will receive the outer ends of 60 the hooks when the cars move toward each other, or, (what amounts to the same thing,) when the flanges *a a* are thus moved apart. The recessed face of the body of the coupler thus serves as a buffer.

The lower recess, F, in each coupler need not be employed, as the other will serve the purpose referred to; and when the lower recess is not employed that part of the body D below the dotted line shown in Fig. 2 may be 70 dispensed with.

G G are extensions or ears projecting from the upper portion of the rear part of the body D, and the couplers are pivoted or hinged to the upper part of the front face of the draw-bar by means of a bolt, H, passing horizontally through the extensions G G and through from side to side of the draw-head. The coupler is thus so hung that when free it will extend forward in a horizontal or nearly horizontal line. 80 It may, however, be rocked or tilted up on the bolt H for the purpose of being uncoupled from its fellow, and for the purpose of automatic coupling, as will hereinafter more fully appear, it being understood that the beveled faces of 85 the hooks E E are so arranged, as shown, as to ride upon each other to engagement as the cars approach each other for being coupled, the upper hook falling down and engaging the other as soon as the flanges *a a* pass each 90 other.

I I are chains extending from the top of the car down to the couplers, to which the chains are securely fastened at a point in front of the bolt H, it being understood that the chains 95 are also fastened to the top of the car.

J is a crank rod or lever arranged horizontally across the end of the car, and at a height to be conveniently reached and operated by a person standing upon the ground. The ends 100 of the lever J are bent downward and then inward, so as to lie against the end of the car,

and also form a handle, and the central part of the lever is bowed or bent to stand outward from the end of the car, as shown at *b* and *b'* respectively.

- 5 The chain *I* is connected to the crank portion *b'*, which stands out directly over the coupler when the cranks at the end of the lever lie against the end of the car. It is to be understood that the lever *J* may be so turned 10 in its bearings as to throw the extension *b* upward. When it is so turned, as it may be by seizing and raising the crank-handles *b b* for that purpose, the hook *E* will be raised and uncoupled from its elbow, owing to the connection of the chain *I* with the coupler and with the lever *J*, and when the lever is released all the parts will move to their proper places for coupling. The hooks may also be uncoupled by the drawing up of the chain by 15 a person on the top of the car, and all the parts will again return to their places as soon as the chain is released.

It will be perceived from the foregoing description and from reference to the drawings 20 that the coupler is simple in its construction and operation, durable, cheap, and effective; that no one need go between the cars to couple them, as the coupling is performed automatically, and that the cars can be uncoupled 25 either at the sides near the ends or from the top, and hence that life is not endangered. The couplers are also capable of being applied with facility. Each coupler proper consists of only one part, or, rather, of two twin parts, 30 not including the means for connecting the couplers to the draw-heads and for uncoupling. The means employed for uncoupling consists of only two parts—the chain and the lever. The width of the hooks should be such as to 35 allow the cars to have all the lateral movement they would be likely to have under ordinary circumstances without becoming uncoupled. The couplers are also adapted, as will be perceived, to cars varying considerably 40 from each other in height.

To adapt these couplers for use in connection with the ordinary coupling pin and link, I pierce the flanges *a a*, as shown at *c c*, to receive the links, and also, as shown at *c' c'*, to 45 receive the pin; and, as will be perceived, cars having such couplings may be coupled with facility to cars provided with couplings embodying my invention, although there may be a considerable difference in the height of the 50 cars. The openings *c* and *c'*, however, are not essential, except for the purpose above set forth.

In the modification shown in Figs. 3 and 4 the couplers do not differ in construction, but 55 in arrangement merely, from those shown in Figs. 1 and 2. They also differ in the respect

that they are so hinged to the draw-head as to swing laterally instead of vertically, the engagement being at the sides instead of at the top and bottom; and to render these laterally-vibrating couplers yielding in their lateral movement, I place behind them the springs *d d*, which also serve to hold these couplers in their proper places for coupling automatically. A corresponding change in 60 the means for uncoupling is also made, the lever being arranged vertically, and its lower crank-arm entering the coupler freely, and the chain extending across the end of the car, as shown.

In the arrangement of coupling shown in Figs. 3 and 4 I would regard it as essential to have a recess, *F*, on each side of the arm *a'*.

Of the two modes of arranging the couplers I deem that shown in Figs. 1 and 2 to be the best, as the uppermost coupler then falls into engagement with its fellow by gravity and without the aid of springs.

I desire to state that I regard concave recesses *F F* as equivalent to the V-shaped form 80 thereof shown and described.

While these couplers will, under all ordinary circumstances, prevent the accidental uncoupling of the cars, they will permit uncoupling by an unusual lateral movement, as 90 when a car jumps the track.

I am aware that hook-shaped automatic couplers have heretofore been made and used, and I do not therefore here intend to claim such broadly; but,

Having thus described my invention, what I claim as new, and desire to secure by Letters Patent, is—

1. The combination of the railway-car draw-heads *B B*, the couplers *C C*, having thereon the double-headed hooks *E E*, and the ears *G G*, each coupler having therein the recess *F*, arranged to receive the head of the engaging-coupling, the coupling-bolts *H H*, for connecting the couplers vibratively to the forward 100 ends of the draw-heads, and means for disengaging the said hooks, substantially as and for the purposes specified.

2. The combination of the railway-car draw-heads *B B*, the couplers *C C*, having thereon the double-headed hooks *E E*, and the ears *G G*, each coupler having therein a recess, *F*, to receive the head of the opposite coupler, and containing the openings *c* and *c'*, the coupling-bolts *H H*, the chains *I I*, and crank-levers *J J*, all arranged and operating substantially as 110 and for the purposes specified.

CHARLES J. BELL.
